FIRING MECHANISM FOR USE WITH A GUN
SYNCHRONIZERPaul H. Dixon, Springfield, Ill., assignor to United
Shoe Machinery Corporation, Flemington,
N. J., a corporation of New Jersey

Application October 9, 1946, Serial No. 702,129

2 Claims. (Cl. 89—133)

1

This invention relates to a 20 mm. aircraft gun and particularly to the breech block assembly of such a gun.

It is an object of the present invention to improve the breech block assembly so that a positive control may be obtained over the timing of the firing pin which comprises a part of the assembly.

In accordance with one feature of the invention a sear releasing member is mounted to rock in a slide key joining breech block slides for movement on the bolt of the breech block assembly, said sear releasing member being actuated to move a sear and thus to release the firing pin for its operative movement upon shifting of a sear slide by a trigger motor which receives impulses from a generator operated by a propeller shaft when the gun is in battery.

In accordance with another feature of the invention, latches are provided which prevent a rebound of the breech block slides.

In the drawings,

Fig. 1 is a plan view, partly in section, of a portion of the breech block assembly, including a firing pin and a sear, and shows also a trigger motor for actuating the sear;

Fig. 2 is a section on the line II—II of Fig. 1;

Fig. 3 is a section on the line III—III of Fig. 1;

Fig. 4 shows a bolt with breech block slides mounted thereon;

Fig. 5 is an exploded view of the sear, a firing pin support and bushing, and a breech block slide key with a sear actuating means; and

Fig. 6 is a plan view, partly in section, of a fragment of the breech block assembly, showing the sear actuating means in the position it assumes at the end of its actuating movement.

The invention is illustrated as embodied in a well-known Hispano Suiza 20 mm. aircraft gun and only the gun parts needed for an understanding of the present invention will be described. These parts mainly comprise the breech block assembly which is mounted in a receiver frame 10 (Figs. 1 and 3) of the gun. Included in the breech block assembly are a bolt 12 (Figs. 1, 3, and 4) and two breech block slides 14 mounted on flanges 16 formed on each side of the bolt 12. The slides 14 are joined by a slide key 18 which passes through a transverse slot 20 (Figs. 2 and 4) of the bolt 12, the slot being somewhat longer than the width of the key 18 in order to permit a movement of the breech block slides 14 relatively to the bolt 12 in a direction parallel to the longitudinal axis of the gun.

A central bore 22 (Fig. 1) of the bolt 12 is machined so as to accommodate the gun firing parts which also form a portion of the breech block assembly. Included in the gun firing parts is a firing pin support 24 (Figs. 1 and 2) held in fixed position in the bore 22 by a retaining pin 26. The forward end of the support 24 engages a bushing 28 which abuts a seat 30 formed in the bolt at the forward end of the bore 22. Mounted

2

in the firing pin support 24 and bushing 28 for movement therewith as well as relative thereto, longitudinally of the bolt, is a firing pin 32. The firing pin 32 is actuated by two springs 34, 36 which surround the rear portion of the firing pin between an annular projection 38 of the pin 32 and a retaining plug 40. The retaining plug 40 is held in fixed position in the bore 22 of the bolt 12 by a locking pin 42 which extends through the bolt 12. When the firing pin 32 is released to effect firing of the gun, the reduced forward end of the firing pin moves through a passage 43 extending forward in the bolt 12 from the center of the bore 22.

15 The firing pin 32 is initially held locked in its cocked position, preparatory to the firing, by a sear 44 (Figs. 1, 2, 3, and 5) which engages a shoulder 46 on the firing pin 32. The sear 44 is movably mounted in the firing pin support 24 (Figs. 1 and 5) and is maintained in a position to lock the firing pin 32 by a leaf spring 48 (Figs. 2 and 3) seated at its opposite ends above the sear in a groove 50 of the bolt 12 and engaging the sear with its midportion.

25 In order to release the firing pin 32 in accordance with the present invention, the sear 44 is moved upward against the pressure of its spring by a novel sear actuating or tripping member 52 mounted to rock in a groove provided in the slide key 18 about an axis extending transversely of the bolt 12. Rocking movement is imparted to the member 52 by a slide 54 which moves transversely of the bolt in a guideway of the slide key 18, as shown in Fig. 5, a cam face 56 (Fig. 3) on the inner end of the slide 54 acting on an inclined face 58 provided on a projection of the tripping member 52.

30 The slide 54 is moved inward to act on the member 52 by a known trigger motor 60 (Figs. 1 and 3) secured to a mounting plate 62 which is carried by a bracket 64 (Fig. 3) attached, in turn, to a gun cradle 66. The bracket 64 is so located on the cradle 66 that the trigger motor 60 is in a position to act on the sear slide 54 when the gun is in its battery position ready to be fired. As has been indicated, the gun with which the trigger motor 60 is used as an aircraft gun intended to operate in synchronism with the propeller shaft of the airplane in which the gun is mounted. An impulse generator (not shown) operated by the propeller shaft transmits impulses to the trigger motor 60 to move the slide 54 inward.

35 The trigger motor 60 is contained in a motor housing 68 (Fig. 1) secured to the aforementioned mounting plate 62. A plunger 70 is moved in the housing lengthwise of the gun against the pressure of a spring 72 by the impulses received from the impulse generator and, through a cam face 74, imparts an inward movement, i. e., a movement in a direction transverse to the longitudinal axis of the gun, to a trigger motor slide 76

mounted in the motor housing 68. The inner end of the slide 76 is positioned immediately opposite the outer end of the sear slide 54, as shown in Figs. 1 and 3, when the gun parts are in their battery positions. Thus, inward movement of the motor slide 76 serves to effect an inward movement of the sear slide 54. Moreover, the slide 76, when moving inward, compresses a spring 78 mounted in a recess of the motor housing 68 between a projection near the outer end of the motor slide 76 and a wall of the housing 68. The springs 72, 78 return the trigger motor parts to their initial impulse receiving position upon firing of the gun.

The trigger motor 60 may be used either on a left-hand or a right-hand gun and is merely secured to the gun cradle 66 at the appropriate gun side. Two sear slides 54 may be provided, one mounted at each side of the slide key 18 in order that the improved breech block assembly may be utilized both in left-hand and right-hand guns without requiring any interchanging or substituting of any breech block assembly parts.

In order to prevent a rebound of the breech block slides 14 at the end of the counterrecoil movement of the gun, each slide is provided with a slot 80 (Fig. 4) in which a latch 82 is mounted for movement relatively to the slide, the latch 82 having a pivotal connection 84 (Fig. 1) with the slide at the forward end of the slot 80. The rear portion of each latch is periodically forced into engagement with a cooperating locking face 86 on the bolt 12 by a plunger 88. The plungers 88 have a sliding movement parallel to the longitudinal axis of the bolt 12 in blocks 90 which are mounted in the rear portions of the slots 80 and may move slightly relatively to the slides 14 in the said slots 80. Normally, the plungers are held in their outer positions relatively to the blocks 90 by springs 92 seated in the blocks behind the plungers, the extent of plunger movement being determined by pins 94 which extend through the blocks 90 and engage in longitudinal grooves 96 in the plungers 88.

Assuming that the gun parts are in their battery positions, the improved breech block assembly functions as follows. When the trigger motor 60 (Fig. 1) receives an impulse from its generator, the plunger 70 moves to the left (as seen in Fig. 1) compressing the spring 72 and moving the slide 76 inward against the pressure of the spring 78. The trigger motor slide 76 acts on the sear slide 54 and forces it inward (Fig. 3) said slide 54, through its cam face 56, rocking the tripping member 52 thus moving the sear 44 (Fig. 2) upward out of locking engagement with the shoulder 46 of the firing pin 32. This releases the firing pin 32 and permits the springs 34, 36 to move the firing pin forward, i. e., to the left, as seen in Figs. 1 and 2, to fire the gun. The trigger motor parts are then returned to their initial positions by the springs 72, 78.

As the gun parts move in recoil, i. e., to the right as seen in Figs. 1 and 2, under the action of expanding gases produced by the explosion of the propelling charge, the breech block slides 14 are first moved rearward in known manner to unlock the breech block assembly. The bolt engaging portions of the latches 82 and the locking faces 86 of the bolt 12 are so shaped that the latches 82 will be cammed out of locking engagement with the bolt 12 by the initial rearward movement of the slides 14, the force of the slides overcoming the pressure of the springs 92 so that the latches force the plungers 88 inward into their blocks 90.

During this initial rearward movement of the slides 14 the key 18 is moved therewith relatively to the bolt 12. In thus moving, the key 18 engages the shoulder 46 of the firing pin 32 and moves the firing pin rearward, simultaneously compressing the springs 34, 36. When the shoulder 46 of the firing pin 32 has moved rearward beyond the sear 44, the spring 48 forces the sear downward into locking engagement with the shoulder 46 (Fig. 2), thus holding the firing pin in its cocked position. A cam face 98 (Fig. 6) formed within the slot 20 of the bolt 12 acts on the sear slide 54 during the relative rearward movement of the key 18 and returns the sear slide 54 to its outer position. The bolt 12 thereupon also moves rearward in recoil and at the end of that movement the breech block assembly parts again move forward, or to the left as seen in Figs. 1 and 2, in counterrecoil.

The plungers 88, under the pressure of their springs 92, seek to swing the latches 82 inward (Fig. 1) into engagement with the bolt 12 upon return of the bolt to its battery position. As the slides 14 reach their battery position, the blocks 90 continue to move forward slightly in the slots 80 (Fig. 4) so that the plungers 88 maintain the latches 82 in engagement with the locking faces 86 of the bolt 12 and prevent the slides from rebounding. The parts of the breech block assembly have now regained their initial or battery positions.

Having now described my invention, what I claim as new and desire to secure by Letters Patent of the United States is:

1. In an automatic gun constructed and arranged to operate in synchronism with the propeller shaft of aircraft and to move in recoil and counterrecoil, a reciprocating breech bolt having a bore, a firing pin support secured in the bore of the breech bolt, a firing pin mounted for movement between cocked and firing positions in the support, springs for moving the firing pin to its firing position, breech block slides guided for movement on the breech bolt during the recoil and counterrecoil of the gun, a key joined to the breech block slides and engageable with the firing pin to move the firing pin to its cocked position against the action of the firing pin springs during recoil of the gun, a sear movably mounted in the firing pin support, a sear spring mounted in the breech bolt in engagement with the sear and tending to move the sear to lock the firing pin in its cocked position, a sear tripping member mounted to rock in the slide key, and a power operated sear slide movable in the slide key to rock the sear tripping member when the gun is in battery.

2. In an automatic gun of the type defined in claim 1, a cam face on the breech bolt constructed and arranged to act on the sear slide during the recoil movement of the gun to move the sear slide into cocked position to be operated during the succeeding cycle of the gun.
